TYPOGRAPHICAL COMPOSING, CASTING,
AND DISTRIBUTING MACHINEDavid S. Kennedy, Brooklyn, N. Y., assignor to
Mergenthaler Linotype Company, a corpora-
tion of New York

Application December 3, 1931. Serial No. 578,632

40 Claims. (Cl. 199—11)

This invention relates to typographical composing, casting, and distributing machines, such as linotype machines of the general organization represented in U. S. Letters Patent to O. Mergenthaler, No. 436,532, wherein circulating matrices are released from a magazine in the order in which their characters are to appear in print and then composed in line, the composed line transferred to the face of a slotted mold, the 10 mold filled with molten metal to form a slug or linotype against the matrices which produce the type characters thereon, and the matrices thereafter returned through distributing mechanism to the magazine from which they started.

In these machines, the matrices are of standard length (1 $\frac{1}{4}$ ") and are formed on their opposite edges at their extreme upper and lower ends with projecting ears which enable them to circulate through the various organs of the machine. 15 Ordinarily, the projecting ears take up one portion ($\frac{1}{8}$ ") of the height or length of the matrices on the casting edges thereof, the alining rib or lip of the mold during casting takes up another portion ($\frac{1}{32}$ ") located immediately above the 20 lower ears, and the lip of the mold cap together with the matrix supporting ledge of the line transported or so-called "first elevator" take up a third portion ($\frac{1}{16}$ ") located immediately below the upper projecting ears of the matrices.

It will be seen, therefore, that the intermediate remaining space ($\frac{1}{16}$ ") which can be utilized for the matrix characters is relatively short and confines them to a range not exceeding 14 pt. for two-letter matrices or 30 pt. for the single or head-letter matrices. This range, however, has been increased somewhat as a result of modern improvements, which provide for a reduction in the thickness of the mold alining rib such that single characters ranging as high as 42 pt. may 30 be employed. These modern improvements do not apply to two-letter matrices because of various other factors which come into play, such as the second alining rib on the mold and the spacing of the matrix supporting rails in the first elevator and other organs of the machine, etc. As a result, the present day machines, so far as machine composition is concerned, are still confined to the production of text and certain classes of advertising work, other matter 35 which requires the use of single letter matrices above 42 pt. or of two-letter matrices above 14 pt. being hand-composed and usually produced by special machines.

The present invention provides a machine of 40 much greater capacity than the standard com-

mercial machines and one which is capable of taking care of the greater part of the work now requiring hand composition. To this end, the machine is organized to handle matrices of different lengths, as, for example, the regular matrices of standard length as well as special matrices of much greater length.

In the preferred embodiment illustrated, the special matrices, like the regular matrices, are formed with projecting ears and tooth combinations to permit their circulation through the machine, but, due to their increased length, they are capable of bearing one or two characters of more than double the normal range in height, and this without resort to the modern improvements above alluded to.

The various improvements and the precise manner in which the special matrices are handled from the time they are released for composition in line until distributed will best be understood from the detailed description to follow.

In the accompanying drawings, the invention is shown merely in exemplified or preferred form and as applied to a linotype machine of standard design, but obviously many changes and variations may be made therein and in its mode of adaptation without departure from its spirit. It should, therefore, be understood that the invention is not limited to any specific form or embodiment except insofar as such limitations are specified in the claims.

In the accompanying drawings:

Fig. 1 is a front elevation of the lower portion of a linotype machine equipped with the present improvements;

Fig. 2 is a vertical section taken through the assembler throat and the lower ends of the magazines, showing the escapements and their actuating devices;

Fig. 3 is a front elevation, partly broken away, of a portion of the assembling mechanism;

Fig. 4 is a vertical section taken through the improved assembler when adjusted to cooperate with the special matrices;

Fig. 5 is a view similar to Fig. 4 but showing the assembler adjusted to cooperate with the regular matrices;

Fig. 6 is a vertical section taken through the line delivery or intermediate channel, showing a regular and a special matrix supported therein on the upper rails;

Fig. 7 is a vertical section taken through the line transporter or first elevator and the parts arranged to cooperate therewith when the elevator attains the upper transfer position;

Fig. 8 is a vertical section taken through the casting mechanism and showing the transporter or first elevator supported in casting position upon the filler piece or interponent;

5 Fig. 9 is a side elevation, partly in section and broken away, of the distributing mechanism, showing it adjusted to cooperate with the special matrices;

10 Fig. 10 is a view similar to Fig. 9, but showing the distributing mechanism adjusted to cooperate with the regular matrices;

15 Fig. 11 is a rear elevation of the distributor box, showing the improved lifting finger adjusted to cooperate with the special matrices;

20 Fig. 12 is an elevation of certain parts shown in Fig. 11 with the lifting finger adjusted to cooperate with the regular matrices;

25 Fig. 13 is a vertical section taken on the line 13—13 of Fig. 12;

30 Fig. 14 is a detail horizontal section taken on the line 14—14 of Fig. 13;

35 Fig. 15 is a face view (actual size) of two special matrices, one bearing two characters and the other a single character; and

40 Fig. 16 is a similar view of one of the regular two-letter matrices.

As shown in Fig. 2, the machine is equipped with three superposed channeled magazines A¹, A², A³, mounted for vertical movement in the machine frame so that any selected one may be brought into operative relation to the assembler entrance or raceway E. Each magazine is provided with its own series of escapements A⁴, the individual units of which comprise a spring-pressed rocking verge a, a fore-and-aft plunger a¹ for operating the verge, and a pair of pawls a² which are projected alternately into the path of the matrices as the verge is rocked about its pivotal axis.

45 The escapements are actuated by a single series of pivoted levers A⁵ mounted in the framework and having their upper ends located in engaging relation to the front ends of the plungers a¹ of the active magazine. Operation of the levers A⁵ is controlled from the finger keys of the keyboard A⁶ through a series of power-operated devices (not shown) and a corresponding series of intermediate vertical reeds A⁷.

50 The assembler entrance B, which includes an upper throat section B¹, is made up as usual of a back plate B², a cover plate B³, and a series of intermediate upright guide plates or partitions B⁴. Matrices released from the magazines are directed downwardly through the entrance and guided thereby onto a constantly driven inclined belt B⁵ (Figs. 1 and 3), which delivers them, one after another, into the assembler C, the latter comprising generally the front and rear side walls C¹, C², respectively, and a hinged gate C³, which latter constitutes part of the front wall and may be rocked forwardly when desired for access to the matrix line.

55 As the matrices enter the assembler, they are stacked in line under the influence of a star-wheel B⁶ which pushes them past the spring retaining pawls c of the assembler and up against a vertical finger b of the yielding assembler slide B⁷.

60 When the matrix line is completely composed, 70 the assembler is raised into registration with the intermediate channel D through which the line, by the active stroke of the delivery slide E, is transferred horizontally from the assembler into the vertically movable transporter or so-called first elevator F. This latter operation starts the

machine automatically and the transporter is thereupon caused to descend with the line to the casting position, where it is supported and sustained upon a vise frame O in front of the active mold, the machine being usually equipped with several molds carried in a rotatable wheel or disc G which is adjustable at will to bring any selected mold into use. Preparatory to the casting of the slug, the mold disc is advanced to carry the active mold into close relation with the matrix line, which is then justified after the intaglio characters thereof, by a slight upward movement of the transporter (to engage the lower projecting ears of the matrices with the lip of the mold), are aligned with the mold slot.

90 After the casting operation, the transporter F rises to its uppermost position for registry with the upper transfer channel H, and the matrices are then transferred onto a second elevator bar which carries them upwardly to the distributing level, the transporter, meanwhile, being returned to its normal position and the mold disc being given a three-quarter turn to carry the mold to the ejecting position.

95 As the cycle of operation is completed, the slug 100 is ejected from the mold and the matrices are pushed off the second elevator bar into a box J from which they are fed, one after another, to the distributor proper and released thereby above their respective magazine channels.

105 So far as described, the parts, their construction, and mode of operation, except as hereinafter pointed out, are or may be the same as those embodied in the commercial linotype machine and in themselves constitute no part of the present invention.

110 The regular two-letter matrices X, which are stored in the lower magazines A² and A³, are each formed as usual (see Fig. 16) with upper and lower projecting ears x¹, x², a V-shaped distributing notch x³, and two superposed intaglio characters x⁴, x⁵, the upper edges of the lower projecting ears x² constituting alining surfaces x⁶ by which the matrix characters are aligned with the mold slot. As these matrices enter the assembler C in 115 the course of composition, they may obtain support upon either or both of two superposed rails c¹, c², which are adapted to sustain them at the proper levels for casting. If the matrices are assembled on the upper rails c¹, their lower characters x⁵ are brought into the casting position, and if they are assembled on the lower rail c², their upper characters x⁴ are brought into the casting position. In either case, as well as when the composed line includes matrices standing on 120 both rails of the assembler C, the transporter F, which carries the line to the mold, is supported directly upon the vise frame O so as to locate the matrix line in the proper casting relation to the mold slot. However, when it is desired to cast 125 from a line of "head-letter" matrices which have but a single character (above 14 pt.), or when a "solid" line of italics (usually confined to the lower characters of two-letter matrices) is desired, the matrices are composed in the lower position on the rail c² and the transporter F arrested at a higher level by an adjustable filler piece or interponent O¹ (Fig. 8), which is mounted on top of the vise frame O and is of the proper thickness to arrest the transporter at the higher 130 level required. Justification of the line between clamping jaws is effected in the usual way by means of wedge-shaped spacers Z of regular construction introduced into the line during composition.

135 140 145 150

The special matrices Y, which are stored in the top magazine A¹, are identical, except as to length and height of character with the regular matrices X being formed (see Fig. 15) with upper 5 and lower projecting ears y¹, y², and V-shaped distributing notches y³. As shown in Fig. 15, one of the special matrices is formed with two superposed intaglio characters y⁴, y⁵, and the other with with a single intaglio character y⁷. The 10 upper edges of the lower projecting ears y², like the lower projecting ears x² of the matrices X, constitute alining surfaces y⁶ by which the characters of these matrices are alined with the mold slot.

15 It may be observed (Fig. 2) that while the escapements A⁴ of the magazine A¹ are similar to those of the magazines A², A³, they are set back from the delivery end of the magazine a distance equal to the difference in length of the matrices X and Y, and the plungers a¹ thereof are made correspondingly longer so as to maintain the connection between the verges a and the actuating levers A⁵. The release of the special matrices Y for composition in line may thus be effected 20 by the manipulation of the keyboard A⁶ through the same series of connections employed for the regular matrices X, that is to say, through the vertical reeds A⁷ and the levers A⁸.

25 Matrices X or Y, when released from their respective magazines, are guided into the assembler C by a chute spring B⁸ which corresponds to that employed in the standard commercial machine but which, as may be noted (see Figs. 1 and 3) is capable of longitudinal as well as lateral adjustment so that it may be set in a high or low position relatively to the assembler to cooperate properly with the long special matrices Y or the shorter regular matrices X. To permit such adjustments, the chute springs B⁸ (best shown in Fig. 40 1) is attached to a base plate B⁹ permanently secured to the back plate B² of the assembler entrance B, and is adjustably mounted on said base plate by means of a screw and slot connection b¹.

30 Ordinarily, the rail c² of the assembler C is fixed and the rail c¹ is retractible, but in the present instance both rails c¹ and c² are made retractible in order to permit the assemblage of the special matrices Y on a pair of fixed rails c³ arranged below the rail c². The rail c², which now becomes an intermediate rail, is common to both the regular and special matrices, being employed, as above stated, to support the regular matrices X in their lower casting position to bring their upper characters x⁴ into use and serving also to support the special two-letter matrices Y in their upper casting position to bring their lower characters y⁵ into use. The retractible rails c¹, c² include short rail sections c⁴ arranged at the receiving end of the assembler C and operable independently by means of small hand levers c⁵ pivotally mounted on the front wall C¹ of the assembler.

35 In composing the regular matrices X, the section c⁴ of the lower rail c² is left in operative position, while the section c⁴ of the upper rail c¹ is moved into or out of operative position according to the level at which the individual matrices are to be composed. In composing the special two-letter matrices Y, on the other hand, the 40 section c⁴ of the upper rail c¹ is left in its inactive or withdrawn position and the section c⁴ of the lower rail c² is moved into or out of active position according to the level at which the individual matrices are to be composed. In composing the special single letters matrices Y, the sec-

tions c⁴ of both rails c¹ and c² are left in inactive position, so that all of the matrices may be composed upon the lowermost fixed rails c³ as required.

45 Due to the unusual length of the special matrices Y, the front and rear walls of the assembler C are provided with upper auxiliary members C⁴, C⁵, extending longitudinally thereof and adapted to sustain the special matrices in upright position when they are supported in the upper position on the intermediate rail c². The sustaining member C⁵ of the rear wall C² is secured to the upper surface thereof by means of small stand-brackets C⁶, and the sustaining member C⁴ of the front wall is secured by means of similar brackets C⁶ to the hinged gate C³. At the receiving end of the assembler, the members C⁴ and C⁵ are provided with springs retaining pawls c⁶, which prevent facewise displacement of the assembled matrices and which correspond to the regular retaining pawls c before mentioned.

50 The intermediate channel D (see Fig. 6), through which the matrices are transferred from the assembler C on their way to the transporter F, is provided as usual near the top with a pair of rails d¹ and near the bottom with a pair of rails d², the rails d¹ being arranged to support the regular matrices X and the special matrices Y by their upper projecting ears when they occupy their lower casting positions in the assembler C, and the rails d² being arranged to support the regular matrices by their lower projecting ears when they occupy their upper casting position in the assembler C. When, however, the special two-letter matrices Y are composed in the upper casting position, they are adapted to obtain the required support in their passage through the channel D upon a third pair of rails d³ which are located directly below the rails d¹ and are arranged to cooperate with the lower projecting ears y² 115 of said matrices.

55 Similar improvements are made in the transporter F, which comprises generally (see Fig. 8) the head portion F¹ made up of the front and rear side walls F², F³, and the intermediate spacing block F⁴; the vertically disposed body portion F⁵ slidably mounted in the vise frame O; and the top flange or bridge member F⁶ which overhangs the vise frame and to which the head portion 120 is secured. The head portion F¹, like the channel D, is provided with a pair of upper rails f¹ common to both the regular and special matrices and which supports both by their upper ears, and with two single superposed lower rails f² and f³ which are devoted to the regular matrices X and the special two-letter matrices Y, respectively, and which support them by their lower ears. The rails f² and f³, for reasons presently to appear, are formed on a retractible slide member F⁷, which (see Fig. 7) is mounted in the front wall F² of the transporter and is held normally 125

retractible under the tension of pull springs F⁸ to locate the rails f², f³ in their active position. The springs F⁸ act upon the member F⁷ through the medium of vertical levers F⁹ which are mounted in recesses F¹⁰ formed in the front wall F² at the opposite ends thereof. These levers (Fig. 7) are provided at their upper or free ends with beveled or cam surfaces f⁴ by which they may be rocked against the tension of the springs F⁸ to retract the member F⁷ and locate the rails in their inactive position.

60 When the transporter F occupies its normal or intermediate position of rest (as in Fig. 1), the 130

supporting rails f^1, f^2, f^3 thereof are adapted to register respectively with the rails d^1, d^2, d^3 of the intermediate channel D, and when the assembler C is raised to position the line between the 5 depending fingers e of the delivery slide E, the rails c^1, c^2, c^3 of the assembler are adapted to register respectively with the corresponding rails of the channel D. Consequently, lines composed of either the regular matrices X or the special 10 matrices Y will be properly supported and sustained in their transfer from the assembler C through the intermediate channel D into the transporter F irrespective of the different levels at which they may be composed.

15 Upon the delivery of a matrix line to the transporter F, the latter descends to the casting position where it is supported at the proper level upon the vise frame O to locate the matrices of the line in operative relation to the selected 20 mold. The mold shown G¹, (see Fig. 8) comprises, generally, a fixed body portion G² screwed fast to the disc G, a cap portion G³ adjustable toward and from said body portion, and a pair of intermediate end walls or liners G⁴ anchored 25 to the cap and body portions. The mold G¹ presents three superposed alining ribs g¹, g², g³, and intermediate grooves g⁴, g⁵, g⁶, the upper and lowermost ribs g¹, g³, being used for the special 30 matrices Y, and the upper and intermediate ribs g¹, g² being used for the regular matrices X. The upper alining rib or lip g¹ is of the usual thickness (7/32") and is formed directly on the body portion G², whereas the ribs g² and g³, for purposes of economy in manufacture, are formed 35 on a separate plate G⁵ arranged beneath the lip and secured to the front face of the body portion G².

40 In casting from the upper characters y⁴ of the special two-letter matrices Y, their lower projecting ears y² are adapted, as the disc G is advanced from the rear, to engage in the lowermost groove g⁶ of the mold G¹, so that the matrices may be alined by the corresponding rib g³; and in casting 45 from the lower characters y⁵ of these special two-letter matrices, their lower ears are adapted to engage in the uppermost groove g⁴ of the mold so that the matrices may be properly alined by the corresponding lip g¹. In both instances, the transporter F is supported at the same level upon the interponent or filler piece O¹. When the regular two-letter matrices X are used, the filler piece 50 O¹ is not employed except when casting solid lines of italics, as before stated, and the transporter is allowed to bank directly upon the vise frame O, the lower projecting ears x² of the matrices being adapted, preparatory to alinement, to engage in either the upper groove g⁴ or the intermediate groove g⁵ of the mold G¹, according to the position 55 the matrices occupy in the transporter.

60 It may be stated at this point, by way of explanation, that the alining surfaces x⁶, y⁶ of the regular two-letter matrices X and the special two-letter matrices Y are located the same distance from the datum line of their respective 65 lower characters (which are inverted and designed for top alinement, as customary), and the same is true of the single letter matrices X and the single letter matrices Y (see Figs. 15 and 16), but since the special two-letter matrices are 70 assembled in their upper casting position on the rail c² (which latter sustains the regular matrices in their lower casting position), lines composed of these special matrices must be presented to the mold at the higher level determined by the 75 filler piece O¹. It will be remembered that the

filler piece is also employed in casting from the regular matrices when the latter, if of the single head-letter variety or even of the two-letter variety, are composed at the lower level. If it should be desired to cast from lines of the special 80 matrices Y having but one character y⁷ (Fig. 15) of a height above 30 pt., a separate stop member or filler piece (not shown) of the appropriate thickness to either supplement the stop member O¹ or to be used independently thereof 85 may be employed. A suitable arrangement for such purpose is shown and described in my prior Letters Patent No. 1,595,947.

90 After the mold disc G recedes to break the contact of the mold G¹ with the matrix line, and the transporter F in its ascent approaches the upper transfer channel H, the slide member F⁷ which carries the two lower rails f², f³ is retracted by the engagement of the cam surface f⁴ of the levers F⁹ with a pair of fixed hardened blocks 95 O² secured to the machine frame (see Figs. 1 and 7). As a result, the matrices X or Y which may happen to stand in an upper position in the transporter are allowed to drop upon the fixed rails f¹ to aline their V-shaped notches x³, y³ 100 with the second elevator bar. Matrices that might fail to drop, for one reason or another at such times, are forcibly depressed as the elevator is brought into registry with the channel H by a stationary bar O³ arranged behind the blocks 105 O² in the vertical path of the matrices.

The channel H is of regular construction and gives support to the spacers Z which are left suspended therein temporarily while the matrices are lifted for distribution, and which are subsequently delivered in the usual way to their storage magazine Z¹ (Fig. 1).

110 Attention is now directed to Figs. 9 to 14, inclusive, which illustrate the improvements in the mechanism for distributing the regular matrices X and the special matrices Y to their respective magazines A¹ and A² or A³.

115 A matrix line transferred from the second elevator bar into the distributor box J is pushed therethrough up against stop shoulders or abutments J¹, J², J³, disposed in pairs and formed on extensions J⁴ of the box rails J⁵. The uppermost pair of shoulders J¹ is common to both the regular and the special matrices, being located in the path of the upper projecting ears x¹ and y¹ of 120 the matrices X and Y, and the two lower pairs of shoulders J² and J³ are individual to the respective matrices, the shoulder J² being located in the path of the lower projecting ears x² of 125 the regular matrices X, and the shoulder J³ being located in the path of the lower projecting ears y² of 130 the special matrices Y.

130 The several pairs of stop shoulders are vertically alined with one another and are arranged to arrest the leading matrix of the line directly 135 above and in the path of a reciprocating finger J⁶ which is adapted to lift the matrices by their lower edges, one after another, above the shoulders and into the receiving end of the distributor K, the latter (see Figs. 9 and 10) comprising a 140 set of three distributor screws K¹ (two upper and one lower) and a single distributor bar K².

145 As the matrices enter the distributor K, they are advanced by the screws K¹ across the rail extensions J⁴ into engagement with the distributor bar K², and thence along the same until they are released above their respective magazine channels. While the several screws K¹ are grouped in the usual way about the distributor bar K², it may be noted (see Fig. 9) that the lower 150

screw K¹, which cooperates with the lower ears of the matrices, is considerably greater in diameter than its companions and is spaced a predetermined distance below them in order to serve both 5 the regular matrices X and the special matrices Y (compare Figs. 9 and 10).

The matrix lifting finger J⁶ (see Fig. 11) is capable of vertical adjustment so as to cooperate with either the regular matrices X or with the 10 special matrices Y, being slidably mounted by means of an intermediate dovetailed rib j¹ (Fig. 14) on a block J⁷ which is carried at one end of a rocking lever J⁸ pivoted to the distributor box J. The lever J⁸ is operated by a constantly rotated 15 face cam K³, through the medium of an anti-friction roller j which is carried at the other end of said lever and held resiliently engaged with the cam by a pull spring J⁹. When the special matrices Y are in use, the finger J⁶ is adjusted 20 to the lower position shown in Fig. 11 so that its upper end may reciprocate in the zone between the lowermost shoulders J³; and when the regular matrices X are in use, the finger J⁶ is adjusted to the upper position shown in Fig. 12 so that its 25 upper end may reciprocate in the higher zone between the shoulders J².

To hold the finger J⁶ in its different adjusted positions, the block J⁷ is provided with a latch pin or detent J¹⁰ mounted transversely in the 30 block J⁷ and arranged to engage one or the other of a pair of corresponding apertures j² formed in the finger J⁶. The detent J¹⁰ (see Fig. 12) is held resiliently engaged in the respective apertures j² by a spring j³, and is provided with a knob or 35 handle J¹¹ by which it may be disengaged therefrom whenever it is desired to adjust the finger J⁶. The block J⁷, as shown in Figs. 11 and 12, is pivoted at its lower end to the lever J⁸ and guided in its reciprocal movements by a fixed cross pin 40 J¹² of the box J against which it is held and maintained in upright position by a pull spring J¹³ anchored to the said lever. This latter arrangement permits the upper end of the finger J⁶ to yield facewise as required under the pressure applied to the matrix line, in order that the individual matrices may gain support upon the upper extension J⁴ as they are lifted above the arresting shoulders J¹.

Matrices released from the distributor bar K² 50 are conducted to their respective magazine A¹, A² or A³ by one or the other of two magazine entrances L¹, L², the entrance L¹ being of ordinary form to cooperates with the regular matrices X, and the entrance L² being of a different form to 55 cooperate with the special matrices Y. The entrances L¹ and L² (as shown in Figs. 9 and 10) are arranged in inverted relation to each other and are rotatably mounted so that either may be brought into the operative position as desired, 60 their individual supporting frames being fastened together to provide a reversible holder L³ which is journaled by means of trunnions l in upright side members of a rocking frame M. The magazine entrances L¹ and L² comprise, respectively, curved 65 base plates L⁴, L⁵, top plates L⁶, L⁷, and series of intermediate partitions L⁸, L⁹, which latter divide them into corresponding series of channels vertically aligned with the magazine channels.

While the base and top plates of the entrances 70 are identical in shape and size the partitions thereof, as between the two entrances, (see Figs. 9 and 10) differ in height or length to correspond to the difference in length of the regular and the special matrices X and Y. In other words, the 75 height of the partitions in the respective en-

trances is such that when the entrance L¹ is brought into the operative position (Fig. 10) the upper ends of the partitions L⁸ thereof will be located the required distance below the distributor bar K² to cooperate properly with the regular matrices X; and when the entrance L² is brought into the operative position (Fig. 9), the upper ends of the partitions L⁸ will be located at a greater distance below the distributor bar K² so as to cooperate properly with the special matrices Y, it being understood that the clearance permitted in practice between the partitions of a magazine entrance and the lower ends of matrices suspended from the associated distributor bar, is limited to a few thousandths of an inch in order to insure their passage into the entrance uninterruptedly as they are released.

The frame M which supports the holder L³ for the magazine entrances L¹ and L² (see Figs. 9 and 10) is pivotally mounted at its lower end between fixed brackets O⁴ of the distributor frame and is operable by a hand lever M¹ connected thereto through an intermediate link M². When the hand lever is raised and lowered, the frame M is swung downwardly and upwardly from and to its normal position shown in Figs. 9 and 10, and the interchange of the magazine entrances L¹ and L² is effected automatically during these operations. The means employed for this purpose is similar to that shown in my prior Patent No. 1,570,258 and includes a pair of fixed cam plates O⁵, O⁶ secured to the distributor frame and arranged to cooperate with a pair of studs l protruding from a rotating block L¹⁰ fastened to the entrance holder L³. The cam plates O⁵ and O⁶ also control the operation of a latch bar P for locking the holder L³ against rotation, said bar being mounted in the frame M and adapted to engage one or the other of a pair of notches l² formed in the block L¹⁰. The precise manner in which these parts function is clearly set forth in the above patent and it will suffice to say that, by merely operating the hand lever M¹, the interchange of the entrances is accomplished and the one selected is located in the operative position.

While the improvements as herein shown and described contemplate the use of the regular matrices X and the special matrices Y separately, it might be found desirable to use them conjunctively, i. e. to mix them in the same line, since 125 the relative position of the characters and alining surfaces between the different matrices (X and Y) are such as to permit assemblage and casting of both from the mold G¹ when the regular matrices X occupy their lower casting position. A proposition of this kind would of course require certain changes in the machine, but could be carried out by merely employing a multiple distributor which would include the ordinary primary distributor or separator, and providing the special matrices Y with deep distinguishing notches to cooperate with the primary distinguishing rail. These and other variations will readily suggest themselves to those skilled in the art and should therefore be considered within the scope of the invention as set forth in the following claims.

Having thus described my invention, what I claim is:

1. In or for a typographical casting machine adapted to be equipped with a set of regular matrices of standard length or a set of special matrices of greater than standard length, a slotted mold presenting a matrix alining rib of a given thickness, the regular matrices being

formed with mold alining surfaces located from the datum line of their individual characters at a distance determined by the thickness of said rib, and the special matrices being formed with 5 similar mold alining surfaces located at the same distance from the datum line of their individual characters, for the purpose described.

2. A combination as set forth in claim 1, characterized by the fact that the regular and special matrices are each formed with two superposed characters and that their respective mold alining surfaces are located at the same distance from the datum line of their lower characters.

15 3. In or for a typographical casting machine adapted to be equipped with a set of regular two-letter matrices of standard length or a set of special two-letter matrices of greater than standard length, a slotted mold presenting an 20 upper alining rib common to both sets of matrices for locating the lower characters thereof in casting relation to the mold slot, and two lower alining ribs, devoted respectively to the individual sets of matrices, for locating the upper characters 25 thereof in casting relation to the mold slot.

4. In or for a typographical casting machine adapted to be equipped with a set of regular two-letter matrices of standard length or a set of special two-letter matrices of greater than standard length, a vertically movable transporter 30 for presenting composed lines of matrices of the different sets to the casting mechanism, means common to both sets of matrices for supporting the matrix lines at one level in the transporter 35 to bring the upper characters of the regular matrices or the lower characters of the special matrices into casting position, and separate means, devoted respectively to the different sets of matrices, for supporting the matrix lines at 40 two other levels in the transporter to bring the lower characters of the regular matrices or the upper characters of the special matrices into casting position.

45 5. In a typographical casting machine adapted to be equipped with a set of regular two-letter matrices of standard length or a set of special two-letter matrices of greater than standard length, the combination of means for composing in line matrices of either set at a given level, and means for presenting the composed lines to the mold at a relatively higher level during casting to bring the lower characters of the respective sets into casting position.

55 6. In a typographical casting machine adapted to be equipped with a set of regular two-letter matrices of standard length or a set of special two-letter matrices of greater than standard length, the combination of a mold, a vertically movable transporter, means common to both the regular and special matrices for supporting them in one position in the transporter, means devoted to the special matrices for supporting them in a higher position in the transporter, and means for arresting the transporter at a common elevated 60 level in casting position, whereby the lower characters of the regular matrices, or the upper or lower characters of the special matrices (according to the position they occupy in the transporter), are brought into casting relation to the mold slot.

7. In a typographical casting machine adapted to be equipped with a set of regular matrices of standard length or a set of special matrices of 75 greater than standard length, the combination of a slotted mold, and means for presenting com-

posed lines of matrices of either set at a common level thereto for casting.

8. In a typographical casting and distributing machine adapted to be equipped with a set of regular two-letter matrices of standard length or a set of special two-letter matrices of greater than standard length, the combination of a transporter movable vertically to carry composed lines of matrices of either set to the casting position and thence to a higher position for transfer, means for supporting the matrices of the respective sets in the transported at different levels for casting, and automatic means for bringing the matrices of the composed lines to a common level preparatory to the transfer operation.

9. A combination as specified in claim 8, characterized by the fact that the matrix supporting means therein referred to includes a retractable member to both sets of matrices and operable automatically as the transporter attains the higher transfer position.

10. In a typographical composing, casting and distributing machine adapted to be equipped with a set of regular two-letter matrices of standard length or a set of special two-letter matrices of greater than standard length, the combination of means for composing the matrices of the individual sets at appropriate levels to bring their upper or their lower characters into casting position, automatic means for presenting the matrices thus composed to the casting mechanism, and means operable subsequent to the casting operation for bringing the matrices of either set to a common level for distribution.

11. In or for a typographical casting machine, 110 a matrix of standard width having upper and lower projecting ears of standard height, said matrix being of substantially greater than standard length to increase the distance between the upper and lower projecting ears on the casting 115 edge of the matrix, as and for the purpose described.

12. In or for a typographical casting machine, 120 a two-letter matrix of standard width formed with upper and lower projecting ears and a V-shaped distributing notch of standard dimensions to permit its circulation through the machine, said matrix being of substantially greater than standard length and the height of the individual 125 characters thereof being increased proportionately.

13. In or for a typographical composing machine adapted to be equipped with a set of regular two-letter matrices of standard length or a set of special two-letter matrices of greater than standard length, an assembler wherein the matrices of either set are composed in line and presenting a lower fixed rail devoted to the special matrices for supporting them with their upper characters in casting position, a higher rail devoted to the regular matrices for supporting them with their lower characters in casting position, and an intermediate rail common to both sets of matrices for supporting them with the lower characters of the special matrices and the upper characters of the regular matrices in casting position.

14. An assembler as specified in claim 13, characterized by the fact that the higher and intermediate rails thereof are both provided with retractable sections, for the purpose described.

15. In or for a typographical composing machine adapted to be equipped with a set of regular two-letter matrices of standard length or a set of two-letter matrices of greater than standard length, an assembler wherein the matrices of

- either set may be composed in line, presenting a fixed rail for supporting the special matrices in their lower casting position, and a rail common to both sets of matrices and serving to support the special matrices in their upper casting position, said rail including a retractible short rail section arranged at the receiving end of the assembled and operable at will to permit the assemblage of the special matrices in both upper and lower positions. 10
16. An assembler as specified in claim 15, and including a third rail for supporting the regular matrices in their upper casting position, and characterized by the fact that the rail therein recited 15 serves also to support the regular matrices in their lower casting position, the said third rail including an independently retractible short section operable at will to permit the assemblage of the regular matrices at both the upper and lower levels. 20
17. In a typographical composing machine adapted to be equipped with a set of regular matrices of standard length or a set of special matrices of greater than standard length, assembling mechanism adjustable to cooperate with the matrices of either set and whereby the regular or the special matrices may be composed in line, as desired. 25
18. In a typographical composing machine adapted to be equipped with a set of regular two-letter matrices of standard length or a set of special two-letter matrices of greater than standard length, assembling mechanism adjustable to cooperate with the matrices of either set and whereby the regular or the special matrices may be assembled in their respective upper or lower casting positions to bring their individual characters into use. 30
19. In a typographical composing machine adapted to be equipped with a set of regular matrices of standard length or a set of special matrices of greater than standard length, the combination of differently located escapements for controlling the release of the matrices of the respective sets, and common key-controlled devices for actuating said escapements. 40
20. In a typographical composing machine adapted to be equipped with a set of regular matrices of standard length or a set of special matrices of greater than standard length, the combination of two series of escapements, one for each of said sets, for controlling the release of the matrices one at a time, and a single series of key-controlled devices for actuating the escapements. 50
21. In a typographical composing machine, the combination of two magazines interchangeable in operative position with each other, one containing a set of regular matrices of standard length and the other containing a set of matrices of greater than standard length, escapements associated with each magazine for controlling the release of the matrices therefrom, and a single set of key-controlled devices for actuating the escapements of the magazine in use. 60
22. In a typographical composing machine adapted to be equipped with a set of regular two-letter matrices of standard length or a set of special two-letter matrices of greater than standard length, the combination of an assembler wherein matrices of either set may be composed in line, means for supporting the matrices of the line at different levels to bring one or the other of their superposed characters into casting position, a line transporter, an intermediate chan-
- nel through which the line is transferred from the assembler into the transporter, and means for maintaining the matrices of the respective sets at their assembly levels during their passage through said channel. 80
23. In or for a typographical distributing machine adapted to be equipped with a set of regular matrices of standard or a set of special matrices of greater than standard length, distributing mechanism adjustable to handle the matrices of one set or the other, as desired. 85
24. In a typographical distributing machine adapted to be equipped with a set of regular matrices of standard length or a set of special matrices of greater than standard length, the combination of a single distributor comprising a distributor bar and a set of matrix conveying screws, and means adjustable to cooperate with either the regular or the special matrices for conducting them from the distributor to their respective magazines. 90
25. In a typographical distributing machine adapted to be equipped with a set of regular matrices of standard length or a set of special matrices of greater than standard length, the combination of two magazines interchangeable in operative position with each other and wherein the respective sets of matrices are stored, a single distributor comprising a distributor bar and a set of matrix conveying screws, and two intermediate magazine entrances movably mounted so that either may be brought into operative relation to the distributor and the magazine in use, one of said entrances being of regular form to cooperate with the regular matrices in conducting them from the distributor to one of said magazines, and the other entrance being of a different form to cooperate with the special matrices in conducting them from the distributor to the other magazine. 100
26. A combination as specified in claim 25, characterized by the fact that the magazine entrances therein recited are arranged in inverted relation to each other and are rotatably mounted for interchange. 110
27. A combination as specified in claim 25, characterized by the fact that each of the magazine entrances therein recited is formed with a series of vertically disposed partition plates and intermediate channels, and that the partition plates as between entrances differ in height or length to correspond to the difference in length of the regular and special matrices. 120
28. In or for a typographical distributing machine adapted to handle regular matrices of standard length or special matrices of greater than standard length, a single distributor comprising a distributor bar and a set of two upper and one lower distributor screws for conveying the matrices along the bar, the two upper screws of said distributor being of a given diameter, and the lower screw being of greater diameter and spaced below the upper screws a distance determined by the different lengths of the regular and special matrices. 130
29. In a typographical distributing machine adapted to handle regular matrices of standard length and special matrices of greater than standard length, the combination of a distributor comprising a distributor bar and a set of matrix conveying screws, a distributor box through which the matrices are advanced for distribution, matrix supporting rails arranged in said box, including an upper rail common to both kinds of matrices, and two lower rails devoted respectively to the 140

different matrices, an abutment formed on each of said rails for arresting the matrices at the receiving end of the distributor, and a reciprocating member for lifting the matrices one after another into the range of action of the distributor screws.

30. In a typographical distributing machine adapted to be equipped with a set of regular matrices of standard length or a set of special matrices of greater than standard length, the combination of a distributor for handling the matrices of both sets, and means for feeding the matrices of either set successively to the distributor.

31. A combination as specified in claim 30, characterized by the fact that the distributor therein referred to comprises a single distributor bar and a set of two upper and one lower distributor screws for conveying the matrices along the bar.

32. In a typographical distributing machine adapted to handle regular matrices of standard length or special matrices of greater than standard length, the combination of a distributor, a distributor box arranged at the receiving end of the distributor and through which the matrices are advanced for distribution, and a lifting finger mounted to reciprocate in the box for feeding the matrices one after another from the box to the distributor screws, said finger being adjustable to different positions so as to cooperate with either the regular or special matrices, as required.

33. A combination as specified in claim 32, including means for locking the finger in its adjusted positions.

34. In a typographical composing machine adapted to be equipped with a set of regular matrices of standard length or a set of special matrices of greater than standard length, the combination of an assembler, a star wheel for stacking the matrices in line as they enter the assembler, and a chute spring provided with an angular extension for deflecting the matrices downwardly into the assembler as they engage the star wheel, said spring being adjustable longitudinally to different positions to cooperate properly with either the regular or special matrices, as required.

35. In or for a typographical composing machine adapted to be equipped with a set of regular two-letter matrices of standard length or a set of special two-letter matrices of greater than standard length, an assembler wherein the matrices of either set are composed in line, said assembler being provided with three superposed rails for supporting the matrices of the respective sets at the different levels required to bring their upper or lower characters into casting position.

36. In or for a typographical casting machine adapted to be equipped with a set of regular two-letter matrices of standard length or a set of special two-letter matrices of greater than standard length, casting mechanism adjustable to cooperate with matrices of either set and whereby slugs may be cast from composed lines of regular or special matrices, as desired.

37. In or for a typographical casting machine adapted to be equipped with a set of regular two-letter matrices of standard length or a set of special two-letter matrices of greater than standard length, a vertically movable transporter for presenting composed lines of matrices of the

different sets to the casting mechanism, said transporter being provided with three sets of superposed rails for supporting the matrices of the respective sets at the different levels required to bring their upper or lower characters into casting position.

38. In or for a typographical casting machine adapted to be equipped with a set of regular two-letter matrices of standard length or a set of special two-letter matrices of greater than standard length, a slotted mold formed with three superposed alining ribs for locating the matrices of the respective sets at the different levels required to bring their upper or lower characters into registration with the mold slot.

39. In a typographical composing, casting and distributing machine adapted to be equipped with a set of regular two-letter matrices of standard length or a set of special two-letter matrices of greater than standard length, the combination of an assembling mechanism adjustable to cooperate with matrices of either set, and whereby the regular or the special matrices may be composed in line as desired, casting mechanism also adjustable to cooperate with matrices of either set and whereby slugs may be cast from composed lines of regular or special matrices, and distributing mechanism likewise adjustable to cooperate with matrices of either set and whereby the composed lines after casting may be restored to their proper place of storage.

40. In a typographical composing, casting and distributing machine adapted to be equipped with a set of regular two-letter matrices of standard length or a set of special two-letter matrices of greater than standard length, the combination of an assembling mechanism adjustable to cooperate with matrices of either set, and including an assembler provided with three superposed rails for supporting the matrices of the respective sets at the different levels required to bring their upper or lower characters into casting position, casting mechanism adjustable to cooperate with matrices of either set and including a movable transporter provided with three sets of superposed rails for supporting the matrices at the different levels at which they are composed in line, and distributing mechanism adjustable to cooperate with matrices of either set and including a distributor box formed with a single set of rails for supporting the matrices of the respective sets at a common level, a matrix lifting finger adjustable vertically to compensate for the difference in length of the matrices of the respective sets as they are supported in the distributor box, a single distributor bar onto which the matrices of the respective sets are fed from the distributor box, and two partitioned magazine entrances interchangeable in position with each other to receive the matrices of the respective sets as they are released from the bar, said entrances having partitions of different lengths to compensate for the difference in length of the matrices of the respective sets as they travel along the bar.

DAVID S. KENNEDY.
